ENGINE STARTER

William M. Reese, Collingdale, Pa.

Application December 16, 1932, Serial No. 647,590

9 Claims. (CL. 290—30)

The invention relates generally to electrical power generating equipment and particularly to starters for internal combustion engines, and more specifically to the provision of a full automatic or semi-automatic mechanical-electric unit which may be used for emergency purposes to provide an emergency source of electric current supply to automatically supply electrical translating devices with electricity when the main source of electric current supply fails or is interrupted.

An object of the invention is to provide mechanical means which when released or placed in condition to function will automatically start the engine to which it is connected, said mechanical starting means being automatically reset by the operations of the engine when placed in condition to be reset and thereafter normally maintained in a non-functioning condition, and the final resetting operations stopping the engine.

Another object of the invention is to provide a mechanical starting means connected with the crank shaft of an internal combustion engine and normally maintained in a non-functioning condition due to means controlled by a source of electric current, said latter means upon failure or interruption of the current causing the mechanical starting means to be released so as to function and thereby start the engine and the actuation of said electrically controlled means due to the return of the electric current supply placing the parts in condition to cause the engine to reset the starting means and the final resetting operations stopping the engine.

Another object of the invention is to provide a mechanical starting means connected with the crank shaft of an internal combustion engine and normally maintained in a non-functioning condition by manually operative control means, the operation of which will release the starter for initially rotating the engine crank shaft, said starter being reset by the engine after the control means has been again manually actuated and the final resetting operations resulting in stopping the engine.

A further object of the invention is to provide a unit including an internal combustion engine, an electric generator operated by said engine and a mechanical starter normally maintained in a non-functioning condition, said starter being released or placed in condition to function by an electrically governed control means upon interruption or failure of a main source of electric current supply with which said control means as well as translating devices are connected, the elec-

tric generator thereafter being operated by the engine to supply current to the same or other translating devices, said starting means being automatically reset by the operations of the engine when placed in condition to be reset due to 5 operation of the control means upon the return of the main source of current and the final resetting operations stopping the engine and shutting off the supply of current from the generator.

With these and other ends in view, this invention consists in the details of construction and combination of elements hereinafter set forth and then specifically designated by the claims.

In order that those skilled in the art to which this invention appertains may understand how 15 to make and use the same, I will describe its construction in detail, referring by numerals to the accompanying drawings forming a part of this application, in which:—

Fig. 1 is a view of the unit, partly in elevation 20 and partly in section looking toward a side of the engine and diagrammatically illustrating one way of making the electric connections.

Fig. 2 is a top plan view thereof with the starter casing in section and the electrical connections eliminated.

Fig. 3 is a view looking at the inner end of the starter which is broken away to show details of construction.

Fig. 4 is a face view of one train of gears in the 30 starter.

Fig. 5 is an end view of the unit opposite to the illustration in Fig. 3, and on a slightly smaller scale, with the weight housing in section.

Fig. 6 is an enlarged fragmentary sectional view 35 of the upper gear shown in Fig. 4.

Fig. 7 is a similar view of the lower gear in the train illustrated in Fig. 4.

Fig. 8 is an enlarged fragmentary section of the clutch on the line 8—8 of Fig. 9.

Fig. 9 is an enlarged view of the starter mechanism with the casing in vertical section and parts broken away and shown in section to illustrate details of construction.

Fig. 10 is a fragmentary sectional view showing a spring as a substitute for the weight. Fig. 11 is a diagrammatic view of the electrical connections between the main supply lines, the switching mechanism, the solenoid and the generator.

Fig. 12 is a diagrammatical view of a double pole double throw switch and its electrical connections.

Fig. 13 is a fragmentary view partly in eleva- 55

tion and partly in section with a diagram of a modified arrangement of electrical connections.

It is highly desirable and often essential that the electric current supply be practically uninterrupted in places of public gatherings, such as theatres, schools, hospitals, hotels and dance or other halls, because should the main or outside current supply fail, the exit lights in the theatres, schools and the like, or other necessary lights

10 in hospitals and the like would be extinguished and electrically operated apparatus stopped, possibly resulting in panics and death, or injury to persons attempting to leave the buildings in darkness.

15 In such cases it is really necessary to have an emergency source of electric current supply derived from a source separate from and independent of the main or outside normal supply and that said emergency source of supply be automatically

20 placed in operation immediately upon failure or interruption of said main or outside normal supply. This result is attained by the use of the full automatic starter as will be obvious from the description below.

25 Whenever the unit is to be used only for electrical power generating purposes rather than as an emergency plant in places, such as farms or small settlements, which are not supplied with electric current from a public service or central 30 commercial supply plant, the semi-automatic device may be used. In any such instance the unit may be placed in operation with practically no effort whatsoever on the part of the person desiring to start the device, and likewise, said person may place the equipment in condition to reset the starter and stop the engine so that it will be ready to again function when desired. In fact a small child can carry out the acts necessary to start and stop the plant.

40 To accomplish either of the above outlined purposes, a generator is driven by an internal combustion engine which is started by mechanism including a weight or equivalent means, such as a spring, to be released or placed in condition to 45 function, either automatically or manually, whenever it is necessary or desirable that the unit operate. In connection with the automatic device there is also provided a control means for releasing the holding mechanism which control 50 means functions in accordance with failure of the main, usual or outside source of electric current supply, said control means being normally held and returnable to a neutral position upon restoration of the normal, usual or outside source 55 of current supply to permit return of the released holding mechanism to its normal position whereby the starting mechanism will be reset and cause the engine to stop. The elimination of the control means provides the semi-automatic device 60 and makes the same manually operative.

In carrying out the invention, 15 represents any internal combustion engine or prime mover which requires separate means for giving an initial start thereto. For purposes of illustrating the invention said internal combustion engine is illustrated as one of the gasoline type provided with a fuel intake manifold 16, an exhaust manifold 17, a spark plug 18 for each cylinder and a crank shank shaft 19 on one end of which is mounted the fly 70 wheel 20. If necessary, the engine may be provided with some means for cooling it and to this end there has been shown an intake 21 communicating with a water jacket and an outlet 22 also communicating with the water jacket at a point 75 distant to the intake 21.

The reference numeral 23 denotes any suitable electrical generator driven by the engine either directly or indirectly, and for purposes of illustration only said generator is shown as directly coupled to the crank shaft of the engine by means of the coupling 24.

In order to supply the necessary high tension current to the spark plugs for igniting the fuel charges drawn into the engine, a magneto 25 has been shown, for purposes of illustration, suitably mounted in any desirable location and driven by the engine either directly or indirectly, but merely for purposes of illustration said generator is shown as being actuated by a belt 26 or its equivalent which belt passes around the fly wheel 20 and a pulley 21 on the magneto.

The starter for giving the initial rotation to the crank shaft of the engine is represented by the numeral 28 and preferably comprises a frame 29 which may be in the form of an enclosure or 2 casing for housing certain parts of the mechanism, particularly the two sets or trains of gears. In this frame is journaled the main shaft 30 which is suitably connected with the crank shaft of the engine, either directly or indirectly and 2 may even be an extension of the crank shaft.

While the starter is illustrated as connected with the end of the engine opposite the generator, this is not absolutely necessary since it could be connected to the outer end of the generator shaft 3 and likewise the generator could be connected with or mounted on the main shaft 30. These are merely details of assembly, but it is desirable that it be known that the invention is not limited to any specific relative locations of the parts.

A countershaft 31 is also journaled in the frame 29 and has a sheave 32 fixed thereto as by a key 33, Fig. 9, and on this sheave is wound any suitable flexible cable 34, such as rope, chain, wire or belt of any cross sectional shape, and said cable may 4 pass over a guide pulley 35 mounted in any suitable and desirable location with a weight 36 secured to the free end of said cable whereby the downward movement of said weight will impart a rotary motion in one direction to the counter- 4 shaft 31. The weight and related parts constitutes a mechanical power means and any other power means, for instance a spring, may be substituted therefor, as will be later again mentioned.

On the countershaft 31 is mounted a gear wheel 37 of a gear train 38. Said gear may be fixed to the shaft or it may be revolved in one direction with the shaft and be freed from said shaft when the latter is revolved in the opposite direction. This can be accomplished by the use of any suitable ratchet mechanism, and for purposes of illustration, a number of balls 39, Figs. 6, 7, and 9, have been shown as suitably recessed within some part of the gear wheel 37 between the circumference of the shaft 31 and arcuate surfaces 40, eccentric to the axis of the gear whereby ball receiving pockets are formed which taper from one end to the other between the surface 40 and the circumference of the shaft so that the balls can wedge between the surface 40 and the circumference of the shaft to bind or connect the gear wheel with the shaft when either is revolved in one direction and whereby the balls can also be freed to permit rotation of either the shaft or gear wheel independent of the other. In order to insure the functioning of the balls regardless of their positions about the shaft, they may be normally forced toward the smaller ends of the ball receiving pockets by springs 41. The advantage of using a ratchet mechanism in con-

nection with the gear 37 is to permit the gear train 38 to remain still under certain conditions which will be apparent from later description.

When the countershaft 31 is revolved by the falling weight, the gear wheel 37 and shaft will be revolving in the direction of the arrow adjacent the gear in Fig. 9. The gear 37 meshes with an intermediate gear 42 which is mounted upon a stub or trunnion shaft 43 carried by the frame 29 so that said intermediate gear will be revolved in the direction of the arrow adjacent thereto in Fig. 9.

The intermediate gear 42 meshes with another gear 44 of the gear train 38 which gear 44 is mounted upon the main shaft 30 which gear must be provided with ratchet mechanism to cause the shaft and gear to revolve together when either is revolved in one direction and permitting either to revolve independently of the other when rotated in the opposite direction, and since the ratchet mechanism is the same as above described, except for the direction of operation, similar reference numerals will be applied to the ratchet mechanisms in Figs. 6 and 7. The difference in the direction of operation will be obvious by reference to Fig. 4.

The gear 44 being revolved in the direction of the arrow adjacent thereto in Fig. 9, when the said gear is connected to the shaft 30, said shaft will be revolved in the same direction and impart the necessary initial rotation to the crank shaft of the engine for starting the latter and also causing the magneto 25 to function to supply the electric current to the spark plugs for firing the charges of fuel drawn into the engine cylinders through the intake manifold 16 from any source of supply, such as a reservoir tank.

As soon as the engine begins to operate due to the firing of the fuel fed thereto and the speed of the shaft exceeds that of the gear train, the shaft 30 will revolve independently of the said gear train because the ratchet mechanism in the gear 44 will free the latter from the shaft 30 and the engine will continue to operate without in any way affecting the starter, and the gear train 38 will stop as soon as the prime mover has spent its force, and said gear train will remain motionless until the operation is started to reset the prime mover, and if the gear 37 has a ratchet mechanism said gear train 38 will remain motionless during the time that the prime mover is being reset, or the ratchet may be eliminated from gear 37 in which case the gear train 38 will revolve while the prime mover is being reset, but in either case said gear train 38 will not affect the shaft 30 while the prime mover is being reset. The operation of the engine will actuate the generator 23 and cause it to generate electric current for use as desired.

In order to return the weight to its elevated position or reset the mechanical power means, the countershaft 31 has a gear 45 mounted thereon so as to revolve independently thereof at certain times and under certain conditions is connected or clutched to the shaft 31 whereby the two will revolve together, and for this purpose, I have shown a ball race 46 connected with said shaft 31 through the medium of the sheave 32, which has been done only for convenience of illustration. A tapered or cone clutch member 47 is movable longitudinally of the shaft 31 for to and fro movement within the ball race and said clutch member 47 revolves with the gear 45, and for this purpose it is shown as splined at 48 to the hub 49 of the gear 45, and said clutch member is

normally forced in an inward direction relative to the ball race by a spring 50.

On the shaft 30 is fixed a gear 64, as by a key 65, which gear meshes with the gear 45 so that when the clutch member 47 is moved inward 5 it will slightly clamp the balls 57 between the cone portion of said clutch member and the walls 58 of the ball race. As soon as a slight pressure is applied to the balls and due to the fact that the gear 45 and the clutch member 47 are revolving 10 in the direction of the arrow in Fig. 9, the balls will be moved toward the smaller ends of the ball receiving pockets so as to clutch said clutch member 47 to the ball race which, in effect, is clutching the gear 45 to the shaft 31 which 15 will cause said shaft 31 to revolve with the gear 45. The gear train will operate from the shaft 31 but if the ratchet mechanism is used in the gear 37, the shaft 31 will be free to revolve without actuating the gear train 38. 20

The main shaft 30 being revolved by the engine, the gear 64 will be revolved in the same direction and will transmit motion to the gear 45 and when the latter is freed from the shaft 31 will merely revolve freely thereon, but when 25 clutched to said shaft 31, as herein shown, due to the inward movement of the clutch member, said gear 45 will revolve the countershaft 31 in the direction opposite to the way it was revolved by the falling of the weight 36 and therefore 30 the cable 34 will be wound upon the sheave 32 and the weight elevated. As soon as the weight reaches its highest elevation and is stopped by contact with some stationary element, to be presently described, the engine will be "choked" 35 or stopped and everything will remain at a standstill until such time as the gear 45 may be again freed from the shaft 31.

After the weight has been elevated and the engine stopped, all of the parts will be at rest and 40 since the gear 37 may be and the gear 45 is, in effect, then fastened to the shaft 31 and since the gear 44 is, in effect, and the gear 64 actually is locked to the shaft 30, the apparatus will be held in the at rest position with the weight elevated until such time as the clutch element is moved outward. 45

As the weight 36 is elevated, it is advisable to gradually lessen its speed and cushion the shock against the stop which may be any stationary 50 element, such as rafters, cross bars or equivalent means 66 and the cushioning means may be a spring 67 or any device that will accomplish the object. For instance, it might be a block of rubber. The weight should be also slowly arrested in its downward movement, which can be accomplished by a spring 68 or other suitable means or by a dash-pot 69 having a relief valve 70. 55

It is obvious that the weight may freely move 60 up and down in any open space or any suitable enclosure. For convenience of illustration only, I have shown said weight as housed in a tube 71 and said tube may be located on a building, within a building, on the ground or even below 65 the ground, and such tube may be of solid material or it may be foraminous, wire screening or lattice work.

In order to move the clutch member 47 in a direction opposite to that imparted by the spring 70, said clutch member is shown as provided with a groove 51 with which coacts the shifting fork 52 fixed to the axle 53, the latter carrying a lever 54 positioned in the path of travel of the core 55 of a solenoid 56 suitably supported in 75

blade with the movable core of the solenoid, as by a link 84.

As shown in Fig. 1, this switch may have two contact terminals 85 and 86 with which the knife blade coacts and one of the main supply lines, as conductor 61, is connected to one of said contact terminals, as 85, while the other contact terminal as 86, is connected by a conductor 87 with one side of the generator 23 and the knife blade is connected by a conductor 88 with one side of the electrical translating devices 89, such as electric lamps. The other side of the translating devices is connected to the main supply line conductor 60 and the other generator lead or conductor 90. The above arrangement permits the normal supply of electric current to pass through the conductor 61, contact terminal 85, knife blade switching element 82, and conductor 88, as well as the conductor 60 to the electrical translating devices 89, since with the normal current supply being fed to the lines the movable core of the solenoid will be in its elevated or raised position, but upon failure of the normal current supply, the solenoid will be de-energized and its core will drop thereby withdrawing the knife blade switching element 82 from the contact terminal 85 and throwing it into the contact terminal 86, and as soon as the generator begins to function at a sufficient speed to produce electric current, said current will be supplied to the translating devices 89 through the conductors 90 and 87, the latter forming a part of the circuit through the contact terminal 86, knife blade 82 and conductor 88. Of course it will be obvious that the translating devices 89 can be supplied directly by current from the main source of supply, and other translating devices may be supplied with current directly from the generator 23. For instance, as shown in Fig. 13, the translating devices 89 may be the lamps in a normal lighting system of a building, whereas emergency lights, may be connected with the generator 23 so that when the normal lights 89 are extinguished due to failure of the main or usual source of supply and the generating plant is started, the emergency lights will be lit by the current from the generating plant. Also if desirable, a double pole double throw switch 96, Fig. 12, can be used for connecting one set of electrical translating devices with either the main or generator sources of supply. In the latter instance the main supply lines 60 and 61 terminate at the contacts 91 and 98 of the switch and the conductors 87 and 90 from the generator 23 terminate at the contacts 99 and 100 of said switch while conductors 101 and 102 connect with the switch blades 103 and 104. The switch blades are connected by the link 84 with the core of the solenoid 56.

As intimated in the beginning of this description, any suitable or equivalent operating means can be used in place of the weight 36, and one such means that is suggested is a spring similar to a clock spring having one end fixed to the shaft 31 as the movable element and the other end fixed to some part of the frame 29 as the anchorage or stationary element so that when said spring is wound up in the same manner as the cable 34 is wound, it will upon release revolve the shaft 31 so as to impart motion through the gear train 38, the main shaft 30 for revolving the crank shaft of the engine and when said shaft 31 is revolved in the reverse direction from the engine through the gears 64 and 45, said spring will be rewound for a future starting operation. The use of such a moving means for the starter will

enable a manufacturer to produce a compact self-contained and simple unitary starter structure that may be shipped to the location where it is to be used in a completely assembled condition so that it will be only necessary to make the electrical connections and attach the main shaft 30 with the crank shaft of the engine.

In the full automatic electrical generating apparatus when the main or ordinary source of current supply fails or is interrupted, the solenoid 56 will be de-energized and its movable core 55 will drop and strike the free end of the lever 54 causing the cone clutch member 47 to be moved outward relative to the ball race for releasing the balls therein, thereby freeing the gear 45 from the shaft 31 thus, in effect, unlocking or unclutching the starting mechanism. Immediately the means for rotating the shaft 31 will function to revolve the same and transmit motion through the gear train 38 to the shaft 30 and since the latter is connected with the crank shaft of the engine, said engine will be given the initial start necessary to cause it to operate.

Simultaneously with the starting of the operations of the starting mechanism, the magneto 25 will be actuated so as to supply the necessary electric current to the spark plugs for firing the charges of fuel drawn into the engine and thereafter the engine will continue its operations so long as it is supplied with fuel or until such time as another condition arises, which will purposely but automatically stop the engine, as will be presently referred to. The operation of the engine will drive the generator 23 so that it will supply a suitable emergency electric current as a substitute for the main or usual supply.

With the beginning of the operations of the starting device, the electrical translating devices will be switched over from the main supply lines to the generator supply lines, if switching mechanism is utilized, but where no switching mechanism is used, such translating devices as are connected with the generator supply lines will be caused to function when the translating devices connected with the main supply lines stop functioning due to failure or interruption of the main current supply.

Likewise, as soon as the starter mechanism has its initial movement, means is operated to supply a cooling medium to the engine and the supply of said cooling medium is to be discontinued at the time the starting mechanism is reset.

So long as the engine continues to run, the cooling medium if from a practically inexhaustible source of supply will keep the engine cool and the power generated in the generator 23 will be fed to the generator supply line for use as desired.

At such time as the current is restored in the main supply line, the solenoid will be re-energized and its movable core 55 will be drawn upward or elevated, thereby relieving the pressure from the lever 54 permitting the spring 50 to act for moving the cone clutch element 47 inwardly relative to the ball race 46, which will place the balls 57 under a slight pressure between the circumference of said clutch element 47 and the walls 58 in the ball race. This slight pressure in connection with the action of the springs on the balls will cause the latter to clamp or clutch the gear 45 to the countershaft 31 and since the gear 45 is revolving at the time of the actuation of the clutch element 47 as above outlined, said countershaft 31 will begin to revolve therewith

but in a direction opposite to the direction to which it was first revolved so as to rewind or reset the means which revolved the countershaft for starting the engine. Any other suitable clutch 5 can be used. During this reverse movement of the countershaft the ratchet mechanism in gear 44 will permit the gear train 38 to revolve free from the shaft 30, but if the gear 37 is provided with a ratchet mechanism, as shown, then said 10 gear train 38 will remain stationary during said reverse movement of the countershaft. As the means for revolving the countershaft in a progressive direction nears the rest position, it will gradually form a drag upon said countershaft 15 and when the dragging or hold-back action has increased to such an extent that the engine can no longer function against the same, said engine will come to a standstill and all of the parts will be in rest or reset positions ready for future 20 starting operations.

To utilize the invention as a semi-automatic apparatus, particularly where there is no main supply of current, the solenoid, switch and component parts may be eliminated. With such an 25 arrangement the lever 54 may be actuated manually and means provided to hold said lever in a depressed position against the action of the spring 50 unless said spring is eliminated so that the lever 54 can be manually operated in either 30 direction.

It is thus seen that in the full automatic or the semiautomatic device the starting mechanism after being released or placed in a condition to 35 actuate will start the engine and then remain inactive until such time as the mechanism is placed in condition for winding up the means which causes the starter to function during its starting operations and when said means has been reset the engine will be stopped.

While any mechanic will readily understand 40 that the parts of the generating plant may be mounted or supported in any suitable manner, the frame of the starter, the engine and the generator have all been shown with base cleats or flanges 81, 45 92 and 93 respectively, which may be used to support said parts upon a base 94.

In lieu of the weight and its flexible cable a spring 95 may be mounted within the sheave 32 with one end of said spring connected to the hub 50 of said sheave and the other end fixed to any suitable part of the casing or housing 28.

Of course it is to be understood that the invention is not to be limited to the exact details of 55 construction herein shown and described as these may be varied within the limits of the appended claims without departing from the spirit of the invention.

Having thus fully described the invention, what is claimed as new and useful is:—

60 1. In a device of the character described, an internal combustion engine, means normally at rest but when in motion imparting an initial movement to the internal combustion engine, and mechanism to transmit motion from the engine to said means for resetting said means to its normal at rest position after said means has functioned to impart the said initial movement to the engine and the same mechanism stopping the engine by the counteraction of said means after said means 65 has reached its at rest position beyond which said means cannot go.

2. In a device of the character described, an internal combustion engine, mechanical power means normally at rest, mechanism to transmit a 70 progressive motion from the mechanical power

means to the crankshaft of said internal combustion engine when the mechanical power means is set in motion, and other mechanism to transmit motion from the engine to the mechanical power means in a retrograde direction for resetting said 75 mechanical power means after it has functioned to impart the said initial movement to the engine, the said other mechanism stopping the engine by the counteraction of said mechanical power means after it has reached its at rest position, 10 each of said mechanisms being inoperative during the time the other is functioning.

3. In a device of the character described, a shaft, an engine, mechanical power means for revolving the shaft, mechanism for transmitting 15 motion from said shaft to the crankshaft of the engine in one direction only and capable of being freed from said shafts to permit the first mentioned one to revolve in a reverse direction and to permit the crankshaft to revolve independently of 20 said mechanism, and other mechanism for transmitting motion from the crankshaft to said first mentioned shaft to reset said mechanical power means by revolving said first mentioned shaft in a reverse direction to the direction it is revolved 25 by the mechanical power means and said second named mechanism being freed from the first mentioned shaft while the first named mechanism is functioning, said mechanical power means through the medium of said second named mechanism 30 stalling and stopping the engine by counteraction of said mechanical power means when said mechanical power means has been completely reset.

4. In a device of the kind described, a main 35 shaft, a countershaft, mechanical power means to revolve the countershaft, mechanism connected with said shafts, said mechanism having means for clutching the same to the shafts whereby a progressive motion may be transmitted from the 40 countershaft to the main shaft but which will permit release of the mechanism from said shafts when the direction of motion of the countershaft is reversed or the speed of the driven element exceeds that of the driving element, other mechanism for transmitting motion from the main 45 shaft to the countershaft, and clutch means for clutching said second named mechanism to the countershaft when the latter is to be revolved in a reverse direction to reset the mechanical power 50 means, the said other mechanism stopping the engine by the counteraction of said mechanical power means through the medium of said other mechanism after said mechanical power means 55 has been reset.

5. The structure set forth in claim 4, in combination with a source of electricity, means controlled by said source of electricity to actuate the clutching means for unclutching the reversing mechanism from the countershaft upon failure of 60 the supply of electricity, and means to clutch the reversing mechanism to the countershaft upon the restoration of the supply of electricity.

6. In an electrical system, in combination with a main source of electrical supply, an emergency 65 lighting unit including a generator, an internal combustion engine for driving the same, mechanical power means for automatically initiating functioning of the engine and means for transmitting motion from the mechanical power means to the 70 engine for starting the latter, consisting of a main shaft, a countershaft revolved by said mechanical power means, mechanism connected with said shafts, said mechanism having means for clutching the same to the shafts whereby a progressive 75

motion may be transmitted from the countershaft to the main shaft but which will permit release of the mechanism from said shafts when the direction of motion of the countershaft is reversed or the speed of the driven element exceeds that of the driving element, other mechanism for transmitting motion from the main shaft to the countershaft, clutch means for clutching said second named mechanism to the countershaft when the latter is to be revolved in a reverse direction to reset the mechanical power means and said other mechanism stopping the engine by counteraction of said mechanical power means through the medium of said other mechanism after said mechanical power means has been reset, means controlled by said source of electricity to actuate the clutching means for unclutching the reversing mechanism from the countershaft upon failure of the supply of electricity, and means to clutch the reversing mechanism to the countershaft upon the restoration of the supply of electricity.

7. In a device of the character described, an engine, a countershaft, mechanical power means for revolving the countershaft, mechanism for transmitting motion from said countershaft to the crankshaft of said engine in only one direction, means to releasably connect said mechanism with said crankshaft whereby the latter may revolve independently of said mechanism and the first mentioned shaft revolve in a reverse direction, and other mechanism including electrically controlled means for automatically causing transmission of motion from the crankshaft to said countershaft for revolving the latter in a reverse direction for resetting said mechanical power means and said second named mechanism being freed from the countershaft while the first named mechanism is functioning, and said second named mechanism stopping the engine by the counteraction of the mechanical power means after said mechanical power means has been reset.

8. In combination, an internal combustion engine including a crank shaft, a generator actuated thereby, a countershaft suitably journalled in a supporting frame, a weight, means to connect said weight with the countershaft whereby the descent of said weight will impart a rotary motion to the countershaft, means to transmit motion from said countershaft to the crank shaft of the engine in one direction only for imparting an initial starting movement to the engine, said means including mechanism whereby it will be freed from the crank shaft when the latter exceeds the critical speed of the countershaft and also permitting a reverse movement of said countershaft, means to transmit motion to the countershaft in a reverse direction from the crank shaft, said means including

mechanism for clutching said means to the countershaft whereby said means may be freed from the countershaft to permit its rotation in a progressive direction, the reverse movement of said countershaft elevating the weight, a main source of electrical supply, means for automatically effecting operation of the clutch means when the main source fails, said clutching means automatically clutching the means for driving the countershaft in a reverse direction to said countershaft to cause the weight to be elevated or reset upon the restoration of the main source of current, a magneto for supplying current to the firing means of the engine actuated by the revolving of the crank shaft, means to supply a cooling medium to the engine, means to control the supply of said cooling medium, and means to operate the last mentioned means at the beginning of the descent of the weight and again when said weight reaches approximately its highest 20 elevation.

9. In combination, an internal combustion engine including a crank shaft, a generator actuated thereby, a countershaft suitably journalled in a supporting frame, a spring to impart a rotary motion to the countershaft, means to transmit motion from said countershaft to the crank shaft of the engine in one direction only for imparting an initial starting movement to the engine, said means including mechanism whereby 30 it will be freed from the crank shaft when the latter exceeds the critical speed of the countershaft and also permitting a reverse movement of said countershaft, means to transmit motion to the countershaft in a reverse direction from the 35 crank shaft, said means including mechanism for clutching said means to the countershaft whereby said means may be freed from the countershaft to permit its rotation in a progressive direction, the reverse movement of said 40 countershaft rewinding the spring, a main source of electrical supply, means for automatically effecting operation of the clutch means when the main source fails, said clutching means automatically clutching the means for driving the 45 countershaft in a reverse direction to said countershaft to cause the spring to be rewound upon the restoration of the main source of current, a magneto for supplying current to the firing means of the engine actuated by the revolving of the crank shaft, means to supply a cooling 50 medium to the engine, means to control the supply of said cooling medium, and means to operate the last mentioned means at the beginning of the unwinding of the spring and again when 55 said spring is approximately wound up.

WILLIAM M. REESE.
